UNITED STATES PATENT OFFICE.

EDWARD BENSON, OF MIAMI, ARIZONA.

SHOE-LACE CLASP.

1,221,656.

Specification of Letters Patent.

Patented Apr. 3, 1917.

Application filed February 10, 1916. Serial No. 77,445.

To all whom it may concern:

Be it known that I, EDWARD BENSON, citizen of the United States, residing at Miami, in the county of Gila and State of Arizona, 5 have invented new and useful Improvements in Shoe-Lace Clasps, of which the following is a specification.

This invention relates to devices for holding in place the bow-knot usually tied in 10 shoe laces, and for preventing the same from untying.

The invention has for its object to provide an efficient and easily applied device of the character stated, and one which is simple 15 in construction, and which can be cheaply manufactured.

With the object stated in view, the invention consists in a novel combination and arrangement of parts to be hereinafter described and claimed, and in order that the same may be better understood, reference is had to the accompanying drawing forming 20 a part of this specification.

In the drawing—

25 Figure 1 is a plan view showing the application of the invention;

Fig. 2 is a plan view of the device;

Fig. 3 is a longitudinal section thereof, and

30 Fig. 4 is a transverse section.

Referring specifically to the drawing, the device consists of two pivotally connected jaw members 5 and 6, respectively, between which the bow 7 of the shoe lace 8 is held, 35 the top plate 5 having an aperture 9 in which the knot 10 of the bow is adapted to seat. The two plates are alike in shape, they being oval and slightly concavo-convex, the bottom of the plates being the concave side.

40 The bottom plate 6 has two upstanding hinge lugs 11 at its edge between which lugs seats a hinge lug 12 depending from the top plate 5, and a pin 13 passing through these matching lugs completes the pivotal 45 or hinge connection between the two plates. A small, flat spring 14 is fastened to the top of the bottom plate 6 by a screw 15 and presses against the lug 12 in a way to hold the two plates in closed position, the plates 50 being thus provided with a spring hinge connection.

In the bottom plate 6 are two spaced apertures 16 located on opposite sides of the center thereof. The aperture 9 of the top 55 plate 5 is at the center thereof.

In use, the top plate 5 is swung up from the bottom plate 6 and the device is placed so that the bottom plate fits the outside of the shoe at the top, with the apertures 16 registering with the two top lacing eyes of 60 the shoe. The two ends of the lace are then passed through the apertures 16 and tied into a bow 7, after which the top plate 5 is swung down toward the bottom plate to clamp the bow, the knot 10 thereof seating 65 in the aperture 9 of the top plate. The device is held in place on the shoe by the lace, and the bow-knot is effectually prevented from untying, the bow being clamped between the two plates. 70

The concavo-convex contour of the plates adapts the same to the curved contour of the shoe where the device seats, and it thus fits the shoe closely without detracting from the appearance thereof. 75

In order that the device may fit over the lacing hooks, the bottom plate 6 has indentations 17 to accommodate said hooks, the indentations being pressed into the plate from the bottom thereof. 80

The device can be easily and quickly applied and removed, and it is simple in construction and therefore inexpensive to manufacture. 85

I claim:

1. A shoe lace clasp comprising a pair of opposite pivotally connected clamping jaws located one above the other, one of the jaws having spaced apertures through which the ends of the lace are adapted to be passed to 90 anchor the clasp to the shoe, and the other jaw having a central bow-knot receiving aperture on opposite sides of which the first-mentioned apertures are located. 95

2. A shoe lace clasp comprising a pair of opposite pivotally connected clamping jaws located one above the other, one of the jaws having spaced apertures through which the ends of the lace are adapted to be passed to anchor the clasp to the shoe, and the other 100 jaw having a central bow-knot receiving aperture on opposite sides of which the first-mentioned apertures are located, the first-mentioned jaw also having bottom indentations at its ends. 105

In testimony whereof I affix my signature.

EDWARD BENSON.
